PHOTOGRAPHIC COLOR CORRECTION
PROCESS

Ralph M. Evans, Rochester, N. Y., assignor to
Eastman Kodak Company, Rochester, N. Y., a
corporation of New Jersey

Application January 28, 1942, Serial No. 428,580

6 Claims. (Cl. 95—2)

This invention relates to processes of subtractive color photography, and more particularly to color correction processes of subtractive color photography.

In the production of pictures in natural color in photographic films of the multilayer type, the successful reproduction of a colored object has always depended upon the proper balance of variables such as emulsion sensitivity, development, and the color of dyes or pigments of which the final picture is composed. Defects in the color of the final picture are generally attributable to improper balance of such variables, and are manifest by the predominance of, or the lack of, one or more colors in the pictures.

In photographic color processes of the bleach-out type, utilizing multilayer films having differently sensitized and subtractively colored emulsion layers, the coloring materials of which are to be bleached-out under influence of developed silver images in the respective layers to form colored images, I have observed a defect in the color-rendering of the subtractive dye images, which is not attributable to faulty absorptions of the dyes composing the images. It appears, that where two adjacent emulsion layers of this type of film are processed according to well-known bleach-out methods, the silver image from black-and-white development in one layer influences bleaching of the dye in an adjacent layer, rather than confining its activity to its own layer. The effect of this is to cause a bleaching of dyes in areas of the adjacent layer where bleaching should not occur, and at the same time, the silver image in the one layer loses its efficiency for influencing the bleaching of dye in its own layer. A similar effect has been observed in multilayer color films which are processed by well-known color-forming development methods.

The object of the present invention is to provide a method of compensation for the adverse effect of an image in one layer of a subtractive color film, upon the formation of a colored image in an adjacent layer. Other objects will appear hereinafter.

These objects are accomplished by using the aforesaid silver image to control the sensitometric characteristics of said adversely affected layer in the manner to be subsequently described.

In the accompanying drawings,

Fig. 1 shows in cross-sectional view, a film of the type useful in the bleach-out process, which is subject to the observed color-rendering defects.

Fig. 2 shows the range of tones of several different colors in a colored original.

Fig. 3 is a representation, when the gray scale is balanced, of the theoretically desired gammas and the effective gammas of silver images in bleaching dyes in a film which has been exposed to the colored object of Fig. 2 and developed black-and-white.

Fig. 4 is a representation of the effective gammas of silver images, before and after balancing the gray scale, in bleaching dyes in a film which has been exposed to the colored object of Fig. 2 and developed black-and-white.

Fig. 5 is a representation of the method of the invention, showing the effect on the effective gammas of the silver images, before balancing the gray scale, of exposing through the top layer silver image and forming a secondary silver image in the middle layer and thereafter bleaching dyes in the region of all of the silver images.

My invention will now be more fully described with particular reference to the accompanying drawings.

The film shown in Fig. 1 may be composed of the materials and be sensitized, colored and processed, as described in Ehrenfried U. S. Patent 2,322,001, granted June 15, 1943, or Seymour U. S. Patent No. 2,231,685, granted February 11, 1941. That is, a support 10 may have coated thereon, in order, red, green, and blue light-sensitive emulsion layers, 11, 12, and 13, colored with dyes roughly complementary to the effective sensitivity of the respective emulsion layers; layer 11 being colored cyan, layer 12 colored magenta, and layer 13 colored yellow. After exposure to an original having the colored images shown in Fig. 2, the film is developed with a black-and-white developer and the dyes in the respective layers are bleached-out under influence of the silver images in the respective layers. Bleaching of dyes may be effected, as described in Patent 2,322,001, under influence of silver images resulting from reduction of rehalogenized images, as well as under influence of originally developed silver images. Accordingly, in this application and the appended claims, where I speak of removing dyes under influence of silver images in the layers, it is to be understood that this includes silver images from original silver halide or rehalogenized silver.

Fig. 3 represents in cross-sectional view, the appearance of the film after development. In the figure, the solid H and D curves represent the theoretically desired gammas of the silver im-

ages in the different layers, produced by exposure of the film to light of the color shown in the squares of Fig. 2 directly above the respective curves, followed by development, which gammas in subsequent bleach-out treatment of the film would effect the correct amount of bleaching of the dyes to give a balanced gray scale. The dotted H and D curves represent the observed effective gammas of the silver images in bleaching dyes, and these curves indicate that the gammas of the silver images in layers 11 and 13 are approximately those theoretically desired, whereas, in layer 12 there appear effective gammas in areas corresponding to exposure with blue and magenta light from the colored object; the effective gammas corresponding to exposure with green and yellow lights of the object are low. Accordingly, the effect of bleaching dyes from the respective layers under influence of the effective silver gammas, is to place green over the blues and yellows, a darkening of the greens and a lightening of the magentas. These are typical defects in color-rendition with which my invention is concerned, and which may be attributed, in the case illustrated, to the effect of the silver image in layer 13 upon the bleaching of dyes in the adjacent layer 12.

I have reasoned that the effective gammas of the silver images, shown by the dotted H and D curves of Fig. 3, before balancing the gray scale, must have had the approximate characteristics shown by the solid H and D curves in Fig. 4, wherein, as before, the dotted lines represent the effective gammas when the gray scale is balanced, for instance, by use of a low contrast emulsion in the middle layer. In Fig. 4, emulsion layer 14 is shown as having a greater thickness than the corresponding emulsion layer 12 of Fig. 3. The reason for this will be evident from the following discussion.

At this point I apply the method of my invention. I take a film of the type shown in Fig. 4 differing from the film shown in Fig. 1, in the respect that the density of the dye, or the thickness of the emulsion, in the middle layer is greater (shown in Fig. 4 as an emulsion layer of greater thickness) and expose the film to a colored object such as shown in Fig. 2. Thereafter, silver images are developed in the respective emulsion layers using a suitable black-and-white developer. As explained above, I have reasoned that at this point the respective gammas of the silver images in the layers will have the characteristics shown by the solid H and D curves in Fig. 4. Since, at least a portion of the respective gammas of the silver images in the middle layer may be attributed to the effect of the top layer silver image on the bleaching of dye in the middle layer, the middle layer is given a partial exposure with green light through the silver image in the top layer and a secondary black-and-white image is developed therein. Thereafter, the dyes are bleached from the layers under influence of silver images therein by use of a bleaching solution as disclosed in U. S. Patent 2,322,001, above cited.

The reason for using an increased amount of magenta dye in the middle layer and developing a secondary image in the layer, is now apparent from consideration of Fig. 5. As in Fig. 4, the solid H and D curves in emulsion layers 15, 16, and 17 indicate the effective gammas of the silver images before the secondary image was developed in the middle layer. The dotted lines represent the H and D characteristics of the secondary silver image formed in the middle layer.

The dot-dash lines show the overall effective gammas of all of the silver images for bleaching dyes in the middle layer, when the silver images in layers 15 and 17 effect the correct amount of bleaching in their respective layers.

In other words, in the areas of the middle layer adjacent to the silver images of the top layer, have been impressed secondary silver images of opposite gammas, and in areas of the middle layer not adjacent to top layer silver, images of uniform density have been formed. When the dyes are bleached from the layers as described above, independent of the silver images therein, so that the gray scale is balanced, dye images are left in the areas of layers 15, 16, and 17 indicated by shading. The process, therefore, has faithfully reproduced the colors of the original object since the effective gammas of the silver images shown by the dot-dash lines of layer 16 and the solid lines of layers 15 and 17 are those required by theory to bleach the proper amount of dyes from the layers as shown by the solid line gammas of Fig. 3. It is also apparent that my process now allows the use of a higher contrast emulsion in the middle layer.

In a manner similar to that described above, my invention may be applied to the case where it is found that the silver image in the bottom layer is adversely effecting bleaching of the dye in the middle layer. However, in this case the corrective exposure is made through the bottom layer silver image.

My process is also applicable to multilayer color films of the type having dyed emulsion layers sensitized to light of wave lengths transmitted by the emulsion layers. For instance, a film having green, red and blue sensitive emulsion layers, colored respectively cyan, yellow and magenta, wherein the magenta layer is over the yellow layer and the cyan layer is below the yellow layer, and in which colored images are formed by the bleach-out process, may be treated by my method. In this film where defects in color-rendition may be attributed to the influence of the magenta layer silver image on the bleaching of dye in the adjacent yellow layer, the defects in color-rendition may be manifested by a bluing of the greens, darkening of the blues, yellowing of the reds and a lightening of the yellows when the gray scale is balanced. To compensate for this, after negative development the middle layer is given a partial exposure through the top layer silver image and a secondary image is developed therein. Hereafter, the dyes in the respective layers are bleached out under influence of silver images in them, by means of suitable dye-bleaching solutions.

In correcting for faulty color-rendition in films of the type described, and others useful in the bleach-out process, practically the only limitation to which my method is subject, is the case where it is found to be impossible to make the necessary supplementary exposure into an adversely affected layer through the image causing the adverse effect, due to the presence of an overlying silver image or dyed layer.

Where it is found that the middle layer image of a film of the type shown in Fig. 1 is adversely affecting bleaching of the dye in either of the other adjacent layers, the image of the aspect not involved may be printed and developed in the film subsequent to the supplementary exposure of the adversely affected layer.

Whereas, my invention has been described in respect to faulty rendition of all shades of col-

ors of the colored object of Fig. 2, from the pure color to black, similar defects in rendition of the tints of the colors from the pure colors to white are observable, and may be compensated for in the manner of my invention as described previously or subsequently hereto.

My invention may also be applied to reversal processes of subtractive color photography wherein colored images are produced by means of color-forming development. Typical films useful in such processes, are those disclosed in Mannes and Godowsky U. S. Patent U. S. 2,252,718, granted August 19, 1941, and Jelley and Vittum U. S. Patent 2,322,027, granted June 15, 1943. In these processes certain color-rendering defects are attributed to the effect of the silver image of first development in one layer, on the color-development of a colored image in an adjacent layer. Where the observed defect is of the same order as observed in the processes of the bleach-out type, the correction is applied in the same general manner as previously described, after first development, by exposing the adversely affected layer through the silver image of the layer causing the adverse effect, with the exception, that it is not always necessary to increase the amount of emulsion in said adversely affected layer, because this may be compensated for in the final steps of reversal exposure and color-forming development. In reversal processes of color-forming development where the coupler compound is incorporated in the emulsion, rather than in the developer, any requirement of increased dye in a layer may be satisfied by incorporation of an additional amount of coupler in the layer.

In reversal processes where it is observed that the silver image from first development in one layer, has an effect upon the formation of a colored image in an adjacent layer, opposite in character to the previously described defects, this may be compensated for in a similar manner. Take the case of a color film such as described in U. S. Patent No. 2,252,718, above cited, having in order upon a support, red, green and blue sensitive emulsion layers, in which are to be developed, respectively, cyan, magenta and yellow dye images. Here it is observed that the negative silver of the bottom layer has an adverse effect upon the development of a dye image in the middle layer, which corresponds, effectively, to insufficient exposure in areas of the middle layer adjacent to the silver images of the bottom layer. In other words, there is a tendency in color-forming development of the middle layer, towards formation of more magenta dye than is required. The method of compensating for this defect consists, after first development of silver images in the layers and their removal from the layers, of reversal exposure and development of the cyan image in the bottom layer, followed by supplementary exposure of the middle layer through the cyan silver and dye image, followed by development of a secondary silver image therein, and finally reversal exposure and color development of the other layers.

The adverse effect may also be compensated for by giving the bottom layer a prolonged reversal exposure to red light after first development, which, due to slight sensitivity of the middle layer to red light will impress a supplementary image therein. Subsequent steps in processing comprise the formation of colored images in all layers by means of color-forming development.

The color corrected films, corrected in the manner described in the invention, may be used as color transparencies for projection, viewing or the like, or these films may be used for printing other pictures in color. For instance, one may print the corrected films onto sensitive films of the same type and apply the color correction methods of my invention for producing color balanced images in the final copy. Similarly, in processes where it is desired to take separate aspects from a color film and later assemble colored images corresponding to these aspects, these aspects may be taken from color films corrected according to my invention and assembled as desired. Also, other processes which compensate for deficiencies in absorption or transmission of subtractive dyes, may be used in conjunction with my processes.

It is to be understood that the disclosure herein is by way of example and that I consider as included in my invention all modifications and equivalents falling within the scope of the appended claims.

What I claim is:

1. In a process of producing subtractive multi-color pictures in a photographic film carrying superposed dyed silver halide emulsion layers sensitized to record different regions of the spectrum, wherein the emulsion layers are exposed, developed and the dyes should be removed only under influence of, and in the region of, silver images in the respective layers, but wherein a developed image in the exposed area of one layer adversely affects removal of dye in an adjacent layer, the method comprising exposing to a colored object, a film of the type described having an increased amount of dye in said adversely affected layer, developing silver images therein, partially exposing the unexposed area of said adversely affected layer through the image in said other layer, said exposure being just sufficient to remove all of the increased amount of dye in those regions of said adversely affected layer which underlie regions free of silver in said one layer, developing a second image in said re-exposed layer and then removing the dyes under the influence of silver images in both layers.

2. In a process of producing subtractive multi-color pictures in a photographic film carrying superposed silver halide emulsion layers sensitized to record different regions of the spectrum and dyed complementary to the sensitivity thereof, wherein the emulsion layers are exposed, developed and the dyes should be removed only under influence of, and in the region of, the silver images in the respective layers, but wherein a developed image in the exposed area of one layer adversely affects removal of dye in an adjacent layer, the method comprising exposing to a colored object, a film of the type described having an increased amount of dye in said adversely affected layer, developing silver images therein, partially exposing the unexposed area of said adversely affected layer through the image in said other layer, said exposure being just sufficient to remove all of the increased amount of dye in those regions of said adversely affected layer which underlie regions free of silver in said one layer, developing a second image in said re-exposed layer and then removing the dyes under influence of the silver images in both layers.

3. In a process of producing subtractive multi-color pictures in a photographic film carrying

superposed silver halide emulsion layers sensitized to record different regions of the spectrum and dyed complementary to the sensitivity thereof, wherein the emulsion layers are exposed, developed and the dyes should be removed only under influence of, and in the region of, the silver images in the respective layers, but wherein a developed image in the exposed area of the outer emulsion layer adversely affects removal of dye in an adjacent layer, the method comprising exposing to a colored object, a film of the type described having an increased amount of dye in said adversely affected layer, developing silver images therein, partially exposing the unexposed area of said adversely affected layer through the image in said other layer, said exposure being just sufficient to remove all of the increased amount of dye in those regions of said adversely affected layer which underlie regions free of silver in said outer emulsion layer, developing a second image in said re-exposed layer and then removing the dyes under influence of the silver images in both layers.

4. In a process of producing subtractive multi-color pictures in a photographic film carrying in order upon a support, red, green and blue sensitive silver halide emulsion layers colored cyan, magenta and yellow, respectively, wherein the emulsion layers are exposed, developed and the dyes should be removed only under influence of, and in the region of, silver images in the respective layers, but wherein a developed image in the exposed area of the yellow layer adversely affects removal of dye in the magenta layer, the method comprising exposing to a colored object, a film of the type described having an increased amount of magenta dye in the green sensitive emulsion layer, developing silver images therein, partially exposing the magenta layer with green light through the image in the yellow layer, said exposure being just sufficient to remove all of the increased amount of magenta dye in those regions of said magenta layer which underlie regions free of silver in said yellow layer, developing a second image in the magenta layer and then removing the dyes under influence of the silver images in both layers.

5. In a process of producing subtractive multi-

color pictures in a photographic film carrying superposed dyed silver halide emulsion layers sensitized to light transmitted by the emulsion layers, wherein the emulsion layers are exposed, developed and the dyes should be removed only under influence of, and in the region of, silver images in the respective layers, but wherein a developed image in the exposed area of one layer adversely affects removal of dyes in an adjacent layer, the method comprising exposing to a colored object, a film of the type described having an increased amount of dye in said adversely affected layer, developing silver images therein, partially exposing the unexposed area of said adversely affected layer through the image in said other layer, said exposure being just sufficient to remove all of the increased amount of dye in those regions of said adversely affected layer which underlie regions free of silver in said one layer, developing a second image in said re-exposed layer and then removing the dyes under influence of silver images in both layers.

6. In a process of producing subtractive multi-color pictures in a photographic film carrying superposed dyed silver halide emulsion layers sensitized to light transmitted by the emulsion layers, wherein the emulsion layers are exposed, developed and the dyes should be removed only under influence of, and in the region of, the silver images in the respective layers, but wherein a developed image in the exposed area of the outer emulsion layer adversely affects removal of dye in an adjacent layer, the method comprising exposing to a colored object, a film of the type described having an increased amount of dye in said adversely affected layer, developing silver images therein, partially exposing the unexposed area of said adversely affected layer through the image in said other layer, said exposure being just sufficient to remove all of the increased amount of dye in those regions of said adversely affected layer which underlie regions free of silver in said outer emulsion layer, developing a second image in said re-exposed layer and then removing the dyes under influence of the silver images in both layers.

RALPH M. EVANS.
